[57] CLAIM

The ornamental design for a cardiopulmonary resuscitation pillow, as shown and described.

DESCRIPTION

FIG. 1 is a perspective view of a cardiopulmonary resuscitation pillow embodying my new design;

FIG. 2 is a rear view thereof;

FIG. 3 is a left elevational view thereof;

FIG. 4 is a front view thereof;

FIG. 5 is a right elevational view thereof;

FIG. 6 is a bottom view thereof; and,

FIG. 7 is a top view thereof.

The broken line showing of a patient on the cardiopulmonary resuscitation pillow is for illustrative purposes only and forms no part of the claimed design.
